UNITED STATES PATENT OFFICE.

EDMUND J. TYLER, OF CHICAGO, ILLINOIS.

APPARATUS FOR PRODUCING ARTIFICIAL RESPIRATION.

1,243,900.

Specification of Letters Patent. Patented Oct. 23, 1917.

Application filed September 20, 1916. Serial No. 121,135.

To all whom it may concern:

Be it known that I, EDMUND J. TYLER, a citizen of the United States, residing in Chicago, in the county of Cook and State of Illinois, have invented certain new and useful Improvements in Apparatus for Producing Artificial Respiration, of which the following is a specification.

This invention relates to apparatus for producing artificial respiration whereby air or oxygen or mixtures thereof may be forced into and carbon-dioxid or other waste products withdrawn from the lungs of a patient, the purpose being to simulate and thereby stimulate respiration which has ceased by reason of asphyxiation or other cause.

It is an object of my invention to provide an apparatus which is simple in construction and easily operable by relatively unskilled persons, whereby the lungs of a patient may be caused to assume their normal function where breathing has ceased but life is not extinct.

A further object of my invention is the provision of an apparatus having means to control the rhythm or speed of operation and the volume and character of the oxygen-containing gas supplied to the lungs of a patient.

30 A further object of my invention is the provision of means to limit the amount of pressure or suction exerted by the apparatus when in operation upon the lungs of the patient whereby all danger of injuring the

35 lungs is eliminated.

Other objects and advantages of my invention will be apparent as it is better understood by reference to the following specification when read in connection with the accompanying drawing, illustrating the preferred embodiment thereof, in which—

Figure 1 is a plan view of the apparatus;

Fig. 2 is a transverse section through the apparatus;

45 Fig. 3 is a section on the line 3—3 of Fig. 2;

Fig. 4 is a detail in section of the mixing valve;

Fig. 5 is a detail partially in section of the mixing valve;

Fig. 6 is a section on the line 6—6 of Fig. 2;

Fig. 7 is a detail in perspective of the cylinder for variably limiting the stroke of the apparatus;

55 Fig. 8 is a view in perspective of the

plunger coöperating with the cylinder illustrated in Fig. 7;

Fig. 9 is a section on the line 9—9 of Fig. 2;

Fig. 10 is a section on the line 10—10 of Fig. 2, and

Fig. 11 is a section on the line 11—11 of Fig. 2.

Referring to the drawing, 1 indicates a frame to which the foot plate 2 is secured and upon which rods 3 are mounted to support the top plate 4. A pressure cylinder 5 and a suction cylinder 6 are, respectively, mounted between the base 1 and the top plate 4 and are provided with plungers 7 and 8 connected by rods 9 to an operating handle 10 whereby the plungers 7 and 8 may be reciprocated in their respective cylinders.

The cylinder 5 is provided with an inlet 11 in which a ball valve 12 is disposed and arranged to seat when the plunger 7 descends. The inlet 11 is connected by a duct 13 in the frame 1 to a pipe 14 (Fig. 2) which is in turn connected to a mixing valve 15 provided with an air inlet 16 (Figs. 4 and 5) and an inlet 17 adapted to be connected to a source of oxygen. The valve 15 further comprises a rotatable member 18 provided with an operating handle 19 and with a plurality of openings 20 of different sizes adapted to register with the inlets 16 and 17. The openings 20 are so arranged that when the opening of greatest diameter registers with one of the inlets 16 or 17 the other inlet is closed but when the smaller openings 20 register with the inlets 16 and 17 their combined cross-sectional area will substantially equal the cross-sectional area of one of the largest openings 20. In other words the areas of the registering openings are inversely proportional to each other. A suitable scale, indicating the position of the member 18, is provided upon the face of the valve 15 so that the operator may readily obtain any desired mixture of oxygen and air.

The cylinder 5 is provided with an outlet 21 (Fig. 9) in which a ball valve 22 is disposed and adapted, through the actuation of the spring 23, to close the outlet when the plunger 7 moves upwardly in the cylinder. The outlet 21 is connected by a duct 24 to a coupling 25 which receives the tube 110 leading to the mouth and nose piece (not shown). The cylinder 6 is provided with

an inlet 26 (Fig. 10) in which a ball valve 27 is disposed and arranged to close the inlet when the plunger 8 moves downwardly. The inlet 26 is connected by a duct 28 to a coupling 29 to which the tube leading to the mouth and nose piece (not shown) is connected. The cylinder 6 is provided with an outlet 29 (Fig. 11) in which a ball valve 30 is disposed and arranged to close the outlet under the actuation of the spring 31 when the plunger 8 moves upwardly.

From the foregoing it will be readily understood that upon each downward movement of the operating handle 10 oxygen-containing gas, in which the desired proportion of oxygen is present, is forced from the cylinder 5 to the lungs of a patient and upon each upward movement of the operating handle 10 waste and other products will be withdrawn from the lungs of a patient to the cylinder 6, being expelled therefrom through the outlet 29 upon the succeeding downward movement of the operating handle 10. Because of the delicate nature of the lungs it is desirable that the pressure exerted thereon when oxygen-containing gas is supplied thereto never exceed five ounces and that the suction exerted when waste products are withdrawn from the lungs never exceed four ounces. Accordingly I provide the plunger 7 with an opening 32 normally closed by a valve 33 which is pressed into engagement with its seat by a spring 34. When the plunger 7 moves downwardly the valve 33 will remain on its seat unless the pressure within the cylinder rises above five ounces in which event the valve 33 will be lifted against the spring 34 to allow the escape of a portion of the gas within the cylinder to the opposite side of the plunger 7. The plunger 8 is similarly provided with an opening 35 normally closed by a valve 36 which is maintained on its seat by a spring 37, the valve 36 being, however, arranged to open when the suction exerted by the plunger 8 exceeds four ounces, whereupon air is admitted to the portion of the cylinder 6 below the plunger 8 to reduce the suction.

As persons of different ages have different lung capacities I provide means for adjustably limiting the effective capacity of the cylinders 5 and 6 which comprises an intermediate cylinder 38 inclosing a cylinder 39 provided with slots 40 of varying lengths. A plunger 41 having a lug 42 thereon is connected by a rod 43 to the operating handle 10 and is arranged to rotate in the cylinder 38 in order that the lug 42 may be selectively disposed to engage one or the other of the slots 40. A disk 44 is secured to the upper end of the rod 43 and is provided with a plurality of notches 45 adapted to be engaged by a latch 46 which locks the disk 44 and consequently the rod 43 and the

plunger 41 in position to engage the desired slot 40. Obviously when the operating handle 10 moves upwardly the plunger 40 will be permitted to move upwardly until the lug 42 engages the end of the slot 40 in which it is disposed.

In order to effectively carry out its desired purpose it is essential to an apparatus of this character that speed of operation be limited to substantially equal the normal rate of breathing. To prevent too rapid operation of the apparatus I provide two auxiliary cylinders 47 (Fig. 3) in which plungers 48 are disposed and connected by rods 49 to the operating handle 10. The cylinders 47 are connected by a duct 50 in which is disposed a rotatable valve 51 having an opening 52 of limited cross-sectional area. Obviously when the operating handle 10 is moved upwardly the plungers 48 create a partial vacuum which must be supplied with air through the restricted opening 52 and similarly when the plungers 48 move downwardly the air must escape through the same restricted opening. By rotating the valve 51 the passage of air from the duct 50 to the outlet 52 may be adjusted so that any desired speed of operation may be obtained. When so adjusted the valve 51 may be locked by screwing the threaded clamping collar 53 against the valve.

From the foregoing it will be apparent that I have perfected an apparatus for producing artificial respiration which may be so adjusted that regardless of the experience or knowledge of the operator the patient cannot be injured and the possibility of reviving the patient is greatly increased. With my apparatus a simple movement quickly adjusts the range of movement of the plungers 7 and 8 in accordance with the age of the patient and the proportion of oxygen contained in the gas supplied to the lungs. The speed of operation of the apparatus and the suction and pressure exerted thereby is automatically regulated and requires no attention after the primary adjustment. The latter features assure against injury of the patient.

It will be apparent that various changes may be made in the form, construction and arrangement of the parts without departing from the spirit and scope of the invention, or sacrificing any of its material advantages, the form hereinbefore described being merely a preferred embodiment thereof.

I claim:

1. In an apparatus of the character described, the combination of top and bottom plates, rods connecting said plates, five cylinders supported between said plates, four of said cylinders being arranged symmetrically about the fifth, plungers in each of said cylinders, an operating handle, means connecting said handle and plungers, outlets

- from said inlets to two of said symmetrically arranged cylinders, automatically operable valves in said inlets and outlets, a duct connecting the other two symmetrically arranged cylinders, and an adjustable valve in said duct having a restricted opening communicating with the atmosphere.
2. In an apparatus of the character described, the combination of top and bottom plates, rods connecting said plates, five cylinders supported between said plates, four of said cylinders being arranged symmetrically about the fifth, plungers in each of said cylinders, an operating handle, means connecting said handle and plungers, outlets from and inlets to two of said symmetrically arranged cylinders, automatically operable valves in said inlets and outlets, a duct connecting the other two symmetrically arranged cylinders, an adjustable valve in said duct having a restricted opening communicating with the atmosphere, and means in said fifth cylinder to selectively limit the stroke of said plungers.
3. In an apparatus of the character described, the combination of a pair of cylinders, an inlet to and an outlet from each of said cylinders, valves in said inlets and outlets, a plunger in each of said cylinders, means for actuating said plungers whereby oxygen-containing gas and waste and other products are alternately supplied to and withdrawn from the lungs of a patient, and means for adjustably limiting the movement of said plungers including an intermediate cylinder, the walls of which are provided with slots of varying depth, a rotatable plunger having a lug thereon adapted to selectively enter one of said slots, and means connecting said plunger to said actuating means.
4. In an apparatus of the character described, the combination of a pair of cylinders, an inlet to and an outlet from each of said cylinders, valves in said inlets and outlets, a plunger in each of said cylinders, means for actuating said plungers whereby oxygen-containing gas and waste and other products are alternately supplied to and withdrawn from the lungs of a patient, means for adjustably limiting the movement of said plungers including an intermediate cylinder, the walls of which are provided with slots of varying depth, a rotatable plunger having a lug thereon adapted to selectively enter one of said slots, and means connecting said plunger to said actuating means, and means for locking said plunger against rotation when adjusted to engage one of said slots.
5. In an apparatus of the character described, the combination of a pair of cylinders, an inlet to and an outlet from each of said cylinders, valves in said inlets and outlets, a plunger in each of said cylinders,
- means for actuating said plungers whereby oxygen-containing gas and waste and other products are alternately supplied to and withdrawn from the lungs of a patient, means for adjustably limiting the movement of said plungers including an intermediate cylinder, the walls of which are provided with slots of varying depth, a rotatable plunger having a lug thereon adapted to selectively enter one of said slots, and means connecting said plunger to said actuating means, and means for preventing the actuation of said plungers beyond a predetermined rate of speed.
6. In an apparatus of the character described, the combination of two pairs of symmetrically arranged cylinders, the respective cylinders of each pair being oppositely disposed, plungers in each of said cylinders, rods connected to said plungers and to a common operating handle, outlets from and inlets to the cylinders of one of said pairs, valves in said outlets and inlets, a duct connecting the other pair of cylinders, and a valve in said duct having a restricted opening communicating with the atmosphere.
7. In an apparatus of the character described, the combination of two pairs of symmetrically arranged cylinders, the respective cylinders of each pair being oppositely disposed, plungers in each of said cylinders, rods connected to said plungers and to a common operating handle, outlets from and inlets to the cylinders of one of said pairs, valves in said outlets and inlets, means for preventing the pressure or suction exerted by said cylinders from exceeding a predetermined limit, a duct connecting the other pair of cylinders, and a valve in said duct having a restricted opening communicating with the atmosphere.
8. In an apparatus of the character described, the combination of two pairs of symmetrically arranged cylinders, the respective cylinders of each pair being oppositely disposed, plungers in each of said cylinders, rods connected to said plungers and to a common operating handle, outlets from and inlets to the cylinders of one of said pairs, valves in said outlets and inlets, a mixing valve connected to the inlet to one of said cylinders, a duct connecting the other pair of cylinders, and a valve in said duct having a restricted opening communicating with the atmosphere.
9. In an apparatus of the character described, the combination of two pairs of symmetrically arranged cylinders, the respective cylinders of each pair being oppositely disposed, plungers in each of said cylinders, rods connected to said plungers and to a common operating handle, outlets from and inlets to the cylinders of one of said pairs, valves in said outlets and inlets,

a mixing valve connected to the inlet to one of said cylinders, a duct connecting the other pair of cylinders, a valve in said duct having a restricted opening communicating with the atmosphere, and means to selectively limit the stroke of said plungers.

10. In an apparatus of the character described, the combination of two pairs of symmetrically arranged cylinders, the respective cylinders of each pair being oppositely disposed, plungers in each of said cylinders, rods connected to said plungers and to a common operating handle, outlets from and inlets to the cylinders of one of

said pairs, valves in said outlets and inlets, 15 a mixing valve connected to the inlet to one of said cylinders, a duct connecting the other pair of cylinders, a valve in said duct having a restricted opening communicating with the atmosphere, a fifth cylinder, 20 and means in said cylinder connected to said operating handle to selectively limit the stroke of said plungers.

EDMUND J. TYLER.
